(57) **CLAIM**

The ornamental design for a butcher block cutting board, as shown and described.

DESCRIPTION

FIG. 1 is a front perspective view of a butcher block cutting board, showing my new design, having wood blocks extending along the length of the board, and an accent piece extending widthwise across the board;

FIG. 2 is one side elevation view of the butcher block cutting board embodiment of FIG. 1;

FIG. 3 is a second side elevation view of the butcher block cutting board embodiment of FIG. 1;

FIG. 4 is a first edge view of the butcher block cutting board embodiment of FIG. 1;

FIG. 5 is a second edge view of the butcher block cutting board embodiment of FIG. 1;

FIG. 6 is a top plan view of the butcher block cutting board embodiment of FIG. 1; and,

FIG. 7 is a bottom plan view of the butcher block cutting board embodiment of FIG. 1.

The disclosed invention comprises wood grain patterns. However, since no two wood grains are the same, the wood grain patterns shown in the disclosed embodiments of the invention are representative of the variation in wood grain patterns that comprise the design of the present invention. The scope of the claim of the present application is intended to cover wood grain patterns present in the materials from which the invention is constructed.
